CLAIM

The ornamental design for a portable air-conditioner for through-hatch marine applications, as shown and described.

DESCRIPTION

FIG. 1 is a side elevation view of a portable air-conditioner for through-hatch marine applications, showing our new design, the opposite side being a mirror image of that shown;

FIG. 2 is a top plan view thereof;

FIG. 3 is a front elevation view thereof;

FIG. 4 is a rear elevation view thereof; and

FIG. 5 is a bottom plan view thereof.

FIG. 1**FIG. 2**FIG. 3

FIG. 4

FIG. 5
